CLAIM

The ornamental design for a watch case, as substantially shown and described.

DESCRIPTION

FIG. 1 is a perspective view of the watch case showing my new design;

FIG. 2 is a top plan view thereof, and the bottom plan view is identical;

FIG. 3 is a front elevational view thereof;

FIG. 4 is a rear elevational view thereof;

FIG. 5 is a left side elevational view thereof;

FIG. 6 is a cross sectional view taken along the line 6—6 of FIG. 3; and

FIG. 7 is a right side elevational view thereof.
